UNITED STATES PATENT OFFICE

148,702

DESIGN FOR A MAILBOX OR SIMILAR ARTICLE

Gustave Holmgren, Sheboygan Falls, Wis.

Application July 24, 1946, Serial No. 131,874

Term of patent 3½ years

(Cl. D74—9)

To all whom it may concern:

Be it known that I, Gustave Holmgren, a citizen of the United States, residing at Sheboygan Falls, in the county of Sheboygan and State of Wisconsin, have invented a new, original, and ornamental Design for Mailbox or Similar Article, of which the following is a specification, reference being had to the accompanying drawing, forming a part thereof.

Figure 1 is a perspective view of the mailbox taken to one side of the front and somewhat above the middle transverse plane;

Figure 2 is a side elevational view of the mailbox; and

Figure 3 is a top or plan view of the mailbox.

My design for a mailbox is characterized by the curved lines on the front, sides and ends in combination with the specific shape of the cover

which presents a drooping appearance over the sides and terminates in an upturned peak approximately two-thirds down the front of the mailbox.

I claim:

The ornamental design for a mailbox or similar article, substantially as shown and described.

GUSTAVE HOLMGREN.
